UNITED STATES PATENT OFFICE.

ALBERT O. BUCKIUS, JR., OF CHICAGO, ILLINOIS, ASSIGNOR TO THE NATIONAL MALLEABLE CASTINGS COMPANY, OF CLEVELAND, OHIO, A CORPORATION OF OHIO.

JOURNAL-BOX.

1,182,834.

Specification of Letters Patent.

Patented May 9, 1916.

Application filed March 16, 1915. Serial No. 14,705.

To all whom it may concern:

Be it known that I, ALBERT O. BUCKIUS, Jr., a citizen of the United States, residing at Chicago, Cook county, State of Illinois, have invented new and useful Improvements in Journal-Boxes, of which the following is a specification, reference being had to the accompanying drawings, in which—

10 Figure 1 shows an elevation of a journal box constructed in accordance with my invention; Fig. 2 is a top plan view thereof, partly in section, on lines II—II of Fig. 5; Fig. 3 is a section on lines III—III of Fig. 15 2; Fig. 4 is a partial rear end view of the box; Fig. 5 shows a section of a form of my invention, taken along the lines V—V of Fig. 2; Fig. 6 is a section along lines VI—VI of Fig. 2; Fig. 7 shows a section of a modified form of my invention, on lines VII—VII of Fig. 8, and Fig. 8 is an elevation thereof.

25 My invention relates to journal boxes of that type in which the top is made of cast metal and the bottom or oil cellar is made of pressed or rolled metal.

30 My invention consists in securing the parts of the box together by a projection and slot engagement and in the constructions which I shall hereinafter describe and claim.

Referring to the drawings, A indicates the top of the box, preferably made of cast metal—either malleable iron or steel—because of its complex shape, and B the oil cellar, preferably made of pressed steel, because of its comparative lightness and strength. The sides of the cellar B may be arranged as shown, with unbroken top 40 edges 2, and the top A is provided with downward extensions 3, between each pair of which a top edge 2 is intended to be inserted, and which serve to reinforce the connections between the parts.

45 The sides have a number of upwardly-extending lugs or projections 4, and the top A has a plurality of slots 5, which flare upwardly and outwardly, and through which the projections 4 are designed to extend. The oil cellar preferably has a flat bottom with its sides and rear end 6 arranged substantially at right angles thereto, so that the opening 7 for the dustguard 50 may be arranged in the bottom instead of in the top of the box. The dustguard wall

55 C may be made integral with the cellar B, but is preferably made in a separate piece and secured thereto by welding. As shown particularly in Figs. 2 and 3, the dustguard wall C has in its forward portion inwardly-turned flanges 8 and 9, which bear against the bottom and sides of the box respectively, while in its upper portion it has outwardly-turned flanges 10, which bear against the sides of the box, and at their rear edges 60 against the rear wall 6, and thus assist in maintaining the dustguard wall 8 in proper relation to the rear end 6 of the box.

65 In securing the parts together, the dustguard wall C may first be united to the oil cellar B by welding the flanges 8, 9 and 10 thereto. The projections 4 of the cellar B may be heated red hot and the top A then placed in position on the cellar with the projections 4 seated in the slots 5; the 70 projections 4 may then be hammered down until they fill the V-shaped slots 5 and form a tight mechanical bond between the top A and cellar B. As the projections cool 75 they will shrink to some extent and still 80 further make tight and secure the joint between the two parts. In Figs. 1, 7 and 8 the projections, marked 4^a, are shown in their original and unswaged condition.

85 In addition to uniting the top A and cellar B by swaging down the projections 4 to form a dovetailed connection, these parts may also be united by welding along the line a and b.

90 In Figs. 7 and 8 I have shown a modification of my invention, in which the top A' of the box is cast integral with a side frame D. In this form the oil cellar B' may be secured to the top in the manner described above.

95 It is obvious that many changes may be made in the constructions which I have shown and described without departing from my invention. For instance, the parts may be united by placing a welding material c (as is shown in Figs. 7 and 8) in the slots around the projections, and then melting this material by an oxy-acetylene torch or any other well known process until it fuses with the projections and with the walls of 100 the slots, thereby producing a welded bond between the top and the bottom.

105 What I claim is:

110 1. A journal box comprised of a top having slots therein and a bottom having pro-

jections thereon, said projections being adapted to seat in said slots and to be secured therein to lock the parts together.

2. A journal box comprised of a top having slots therein and a bottom having projections thereon, said slots having upwardly flaring walls, the projections being adapted to seat in and to be secured in said slots.

3. A journal box comprised of a top having slots therein and a bottom having projections thereon and adapted to seat in said slots, the said projections being adapted to be upset in said slots for locking the parts together.

15 4. A journal box comprised of a top having V-shaped slots therein and a bottom having projections on its upper side edges, the projections being adapted to be secured by a dovetailed engagement in said slots.

20 5. A journal box comprised of a top portion and a bottom portion made separately, said top portion having vertically-extending slots, the upper ends of said slots being of greater cross-sectional area than the bottom ends thereof, the bottom portion of said box comprising an oil cellar with vertically-extending side walls, tongues extending vertically from the upper edges of said side walls and adapted to enter said slots, and

25 means for securing said tongues within said slots.

30 6. A journal box comprised of a top portion and a bottom portion made separately, said top portion having vertical slots therein, said bottom portion comprising a metal

cellar and having upwardly-extending sides, projections extending vertically from the upper edges of said sides and adapted to register with the slots in the top portion, the said projections being adapted to be secured in said slots by heat and pressure to unite the parts of the journal box together.

40 7. A journal box consisting of a top, and an oil cellar, the said parts having a slot and projection engagement, the oil cellar being of substantially rectangular shape at its rear end, and having a dustguard opening on its under side.

45 8. A journal box consisting of the following parts: a top, an oil cellar, a dust guard wall, means for uniting the top and oil cellar, the dust guard wall having flanges bearing against the sides and bottom of the cellar and adapted to be welded thereto, and the oil cellar having an opening in its bottom between the dustguard wall and the rear end of the box, adapted for the insertion and removal of a dustguard.

50 9. A journal box consisting of a separately formed top and a separately formed oil cellar, the top having downward extensions forming recesses for the top edges of the sides of the oil cellar, the said top edges having also projections coöperating with slots in the upper face of the top and being adapted to unite the parts together.

55 ALBERT O. BUCKIUS, JR.
